US00D908612S

(12) **United States Design Patent** (10) **Patent No.:** **US D908,612 S**
(45) **Date of Patent:** **** Jan. 26, 2021**

(54) **CHARGER AND BATTERY**

(71) Applicant: **Techtronic Cordless GP**, Anderson, SC (US)

(72) Inventors: **Joseph Sexton**, Charlotte, NC (US); **Shuang Lin**, Charlotte, NC (US); **Somnanritha Chan**, Charlotte, NC (US); **Benjamin Shrader**, Newton, NC (US); **Bradley Hooley**, Charlotte, NC (US)

(73) Assignee: **Techtronic Cordless GP**, Anderson, SC (US)

(**) Term: **15 Years**

(21) Appl. No.: **29/707,712**

(22) Filed: **Sep. 30, 2019**

(51) LOC (13) Cl. **13-02**

(52) U.S. Cl.

USPC **D13/107**; D13/103

OTHER PUBLICATIONS

Hoover Battery Pack, Applicant sold in the U.S. a battery similar to the one illustrated in Appendix A on Mar. 18, 2014.

Primary Examiner — Rosemary K Tarcza

(74) *Attorney, Agent, or Firm* — Michael Best & Friedrich LLP

(57) **CLAIM**

We claim the ornamental design for a charger and battery, as shown.

DESCRIPTION

FIG. 1 is a perspective view of a charger and battery according to a first embodiment.

FIG. 2 is a top plan view of the charger and battery of FIG. 1.

FIG. 3 is a bottom plan view of the charger and battery of FIG. 1.

FIG. 4 is a side view of the charger and battery of FIG. 1.

FIG. 5 is an opposite side view of the charger and battery of FIG. 1.

FIG. 6 is a front view of the charger and battery of FIG. 1.

FIG. 7 is a rear view of the charger and battery of FIG. 1.

FIG. 8 is a perspective view of a charger and battery according to a second embodiment.

FIG. 9 is a top plan view of the charger and battery of FIG. 8.

FIG. 10 is a bottom plan view of the charger and battery of FIG. 8.

FIG. 11 is a side view of the charger and battery of FIG. 8.

FIG. 12 is an opposite side view of the charger and battery of FIG. 8.

FIG. 13 is a front view of the charger and battery of FIG. 8; and,

FIG. 14 is a rear view of the charger and battery of FIG. 8.
